UNITED STATES PATENT OFFICE.

CHARLES INWARD, OF OSAGE, IOWA.

LATCH.

SPECIFICATION forming part of Letters Patent No. 288,639, dated November 20, 1883.

Application filed June 5, 1883. (Model.)

To all whom it may concern:

Be it known that I, CHARLES INWARD, a citizen of the United States, residing at Osage, in the county of Mitchell and State of Iowa, 5 have invented a new and useful Door-Latch, of which the following is a specification, reference being had to the accompanying drawings.

This invention relates to latches for doors, 10 &c.; and it consists in certain improvements in the construction of the same, which will be hereinafter fully described, and particularly pointed out in the claim.

In the drawings hereto annexed, Figure 1 is 15 a perspective view of the device complete. Fig. 2 is a horizontal sectional view of the same. Fig. 3 is a vertical sectional view on the line *x x* in Fig. 2. Fig. 4 is a detail view, in perspective, of the casing with parts broken 20 away, so as to expose the sliding wedge, and Fig. 5 is a perspective detail view of the latch detached from the casing.

The same letters refer to the same parts in 25 all the figures.

25 A in the drawings designates the base-plate, which is formed at one end with a casing, B, the front side or face of which has a recess, C, surrounded by an annular flange, D, to receive the neck or shank of the knob or handle by 30 which my improved latch is in practice intended to be manipulated. The said handle, which is shown only in Fig. 2 of the drawings, is provided with a stem, E, square or polygonal in cross-section, which passes through a 35 correspondingly-shaped eye, F', in the inner end of the latch F. The latter, which is thus pivoted in the casing B, extends through a slot, G, in the side of the latter, and under a keeper, H, at the outer end of the base-plate, 40 beyond which it projects, as at I, so as to be capable of engaging a catch which is to be attached to the door-post, but which is not shown in the drawings, and which forms no part of my invention.

45 J is a spring suitably attached to the base-plate A, and forcing the latch F in a down-

ward direction, so that it will automatically engage and be held in contact with the locking-catch to which reference has been made above.

50 Between the keeper H and the face of the latch is fitted a sliding plate, K, having a handle, L, which extends through a longitudinal horizontal slot in the face of the keeper, so as to be readily manipulated. The said sliding 55 plate has upon its inner side a wedge-shaped projection, M, adapted to engage a stud or projection, N, upon the face of the latch. It will be seen that by means of the said wedge-plate the latch may be locked and held securely 60 in either a raised or lowered position, thus enabling it to be either locked when in engagement with the locking-catch or held raised, so as to be prevented from engaging the said catch.

65 My improved latch is exceedingly simple in construction, durable, and useful for a variety of purposes. Its simplicity of construction renders it not liable to get out of order, and it may be manufactured at a small expense.

70 Having thus described my invention, I claim and desire to secure by Letters Patent of the United States—

75 As an improvement in latches, the combination of the base-plate A, having casing B and keeper H, the stem E, latch F, mounted upon the said stem, and having the stud or projection N, the spring J, the plate K, fitted to slide under the keeper H, and having a wedge-shaped projection, M, adapted to engage the 80 stud N upon the latch, and a thumb-piece projecting from the slide K through a slot in the face of the keeper H, all arranged and operating substantially as set forth.

85 In testimony that I claim the foregoing as my own I have hereto affixed my signature in presence of two witnesses.

CHARLES INWARD.

Witnesses:

W. M. C. MOSS,
W. E. OWEN.
